UNITED STATES PATENT OFFICE

2,095,356

APPARATUS FOR TREATING LIQUIDS

Lawrence J. Davidson, Chicago, Ill.

Application January 2, 1935, Serial No. 187

3 Claims. (Cl. 99—265)

This invention relates to improvements in apparatus for treating liquids of any consistency by the application of pressure.

An object of the invention is to provide an emulsifying device in which there are no moving parts, such as swirlers, discs, valves, springs, baffles, agitators, pistons or the like, to thereby greatly simplify the construction, increase the durability and decrease the cost of the apparatus.

10 A further object of the invention is to provide an emulsifying device which, due to its simplicity of construction, can be used for treating liquids of a highly adhesive nature which cannot be treated effectively by apparatus of this type now generally in use.

15 A further object of the invention is to provide an emulsifying device in which all parts are readily accessible for cleaning or sterilizing, thereby ensuring a sanitary apparatus.

20 A further object of the invention is to provide an apparatus in which complete emulsification or homogenization can be effected by applied pressures far below those generally required in such apparatus.

25 To attain these objects, and other objects which will be apparent from the following description, I provide a device having inlet means for admitting the liquid to be treated, a compression chamber communicating with said inlet means, 30 and a plurality of outlet passages leading from said compression chamber to the exterior of said device, said outlet passages being of such size and shape that the liquid is retained under pressure within the compression chamber until 35 the desired treatment has been effected.

In order to facilitate cleaning, the device may be provided with a removable plug at either end or at both ends of the compression chamber. Where it is necessary or desirable to eliminate 40 splashing or to concentrate the flow of the material or liquid discharged from the outlet passages, a plate or plates, or other suitable deflecting means, may be attached to the exterior of said device in such a manner as to form a 45 space or channel between said deflecting means and the surface or surfaces of said device in which said outlet passages are located.

The device is preferably made from a solid piece of stainless steel, but may be made from 50 any non-corrosive material which will not react with or contaminate the liquid which is to be treated and which is capable of withstanding the pressure which will be created in said device. The device may be of any suitable size or shape. 55 The compression chamber is preferably formed

by drilling a hole straight through the solid piece of material and inserting a removable plug at either end or at both ends of the hole. Where it is desired to use one end of the compression chamber as the inlet means, one end only is 5 closed by a removable plug. Preferably, however, the inlet is located at right angles to the compression chamber and at a point approximately midway between the ends of said compression chamber, so that the pressure within said chamber will be evenly distributed. This inlet means is formed by drilling a hole from the exterior to said chamber.

10 The plurality of outlet passages are also preferably disposed at right angles to said compression chamber, and are formed by drilling holes from the exterior to the compression chamber.

15 The relation between the size of the outlet passages and the size of the central chamber should be such that the sum of the diameters of all the outlet passages at their point of exit from the compression chamber is less than the diameter of the compression chamber. For most liquids, the sum of the diameters of the outlet 20 passages at their point of exit from the compression chamber should be from 35% to 70% less than the diameter of said compression chamber. For non-adhesive liquids having a low fat content, such as milk or tomato juice, the sum 25 of the diameters of the outlet passages at their point of exit from the compression chamber may be as high as 80% of the diameter of the compression chamber.

30 For efficient emulsification of dairy products at moderate pressures, it has been found desirable 35 to give each outlet passage a diameter of approximately .0145 inch at its point of exit from the compression chamber. The size of the outlet passage will, of course, vary according to the liquid which is to be treated, the treatment which 40 is desired and the amount of pressure which is to be applied.

35 The outlet passages should be so spaced from each other that the intervening walls will be of sufficient strength to withstand the pressure, and 45 said outlet passages should be so distributed throughout the length of said compression chamber that no large area of the compression chamber will be without an outlet passage. By so distributing the outlet passages, the formation of 50 dead spaces in the compression chamber is prevented.

45 By my invention I also provide a new combination or assembly. This combination consists essentially of my new device above de- 55

scribed and means for drawing the starting liquid from a source of supply and forcing it into and through said device. This means is preferably a rotary pump of the sanitary twin-impeller type now commonly used for handling dairy products, but may be any pump which is capable of constantly delivering the liquid to and maintaining the required pressure in said device.

The pump is preferably provided with an external by-pass and pressure gauge, so that the pressure which is applied to the liquid may be accurately measured and controlled.

My new device may be connected directly to the discharge side of the rotary pump, or there may be intervening connections.

With the combination of the pump and my new device it is possible to reconstitute milk and cream at a pressure of approximately 125 pounds per square inch, whereas, so far as I am aware, the lowest pressure heretofore used for this purpose in power-driven emulsifiers is approximately 225 pounds per square inch.

Furthermore, with this new combination, it is possible to produce sweetened condensed milk having an 80% solids content at a pressure of approximately 175 pounds per square inch, whereas known power-driven apparatus for this purpose require a pressure of approximately 1000 pounds per square inch.

Also, my new combination is capable of homogenizing chocolate syrup with an applied pressure of approximately 350 pounds per square inch, as compared with approximately 650 pounds per square inch in known apparatus.

The fact that my new combination can successfully operate at these new lower pressures means a tremendous saving, both in the cost of the apparatus itself and in the cost of operation, because the cost of motors and the cost of power to actuate the motors constitute a very substantial part of the total cost in connection with such apparatus.

The invention will be best understood by reference to the accompanying drawing, in which—

Figure 1 is a view in elevation showing a preferred form of my new device, the internal construction being shown in dotted lines;

Figure 2 is a sectional view taken on the line 2—2 of Figure 1;

Figure 3 is a sectional view taken on the line 3—3 of Figure 1;

Figure 4 is a view in elevation of a modified form of my device, with a part broken away to show the internal construction;

Figure 5 is a sectional view taken on the line 5—5 of Figure 4;

Figure 6 is a sectional view taken on the line 6—6 of Figure 4;

Figure 7 is a sectional view showing a modified form of my new device; and

Figure 8 is a diagrammatic view showing my new device in combination with a rotary pump.

Referring to Figures 1, 2, and 3, the device 1 has a compression chamber 2 and a plurality of outlet passages 3 leading downward from the compression chamber to the bottom surface of said device. Each outlet passage 3 is connected to the compression chamber 2 by means of a smaller passage 3a. Each outlet passage 3 is inwardly tapered at the place where it connects with the smaller passage 3a, as shown at 4. The ends of the compression chamber are closed by means of removable plugs 6. An inlet passage 5 to the compression chamber 2 is provided at right

angles to and at a point approximately midway between the ends of said compression chamber.

Figures 4, 5, and 6 show a modified form of my new device. In this embodiment, the device 1 is of rectangular shape, and the inlet passage 5 is disposed at one end of the compression chamber 2, the other end of said chamber being closed by a removable plug 6. The outlet passages 3 issue at right angles from both sides of the compression chamber 2. Plates 7 are fastened to each side of the device by means of bolts 8. Each plate 7 has a recess 9 in its inner surface so as to form a channel 10 with the side of the device. This modification is advantageous where it is desirable to prevent splashing and to concentrate the flow of the liquid discharged from said outlets 3.

Figure 7 shows another form of my new device. In this embodiment, the device 1 is substantially square in shape, and has a compression chamber 2 which may be formed by casting. The device is provided with inwardly-extending flanges 1b adapted to screw on to a screwthreaded plug 11 fastened to the end of the supply pipe 5. The outlet passages 3 issue from the bottom of the compression chamber 2. This embodiment is cheaper to make than the embodiments shown in Figures 1 to 6, inclusive, and may be advantageous where a small device is desired.

Figure 8 shows my new device in combination with a rotary pump. The structure and operation of this combination are as follows:

The materials or liquids to be treated are placed in a tank A where they are mixed and preheated if necessary. Through a pipe 20 the material or liquid is drawn from the tank A by means of a rotary pump B of the twin-propeller type, actuated by any suitable power such as an electric motor. The rotary pump B forces the liquid into a pipe 5, in which the pressure is measured and controlled by means of by-pass 21 leading back into pipe 20. This by-pass 21 is provided with a valve 22 and a pressure gauge C. The material or liquid is forced through the pipe 5 into the compression chamber of the emulsifying device 1. Due to the constant pressure produced by said rotary pump and the retardation in flow caused by the size and shape of the outlet passages, the liquid is retained under pressure within said compression chamber until the desired emulsification has been effected. The emulsified material flows out through the outlet passages of the device 1 into a reservoir D, from which it passes over cooling coils E and into a storage tank F. All connections in this assembly should be of the sanitary type now used in dairy equipment.

Some examples of the applications of the invention are:

Producing milk, cream, whipping-cream and condensed milk from unsalted sweet-cream butter, powdered milk and water;

Producing sweetened condensed milk from unsalted sweet-cream butter, powdered milk, sugar and water;

Producing ice-cream mix from unsalted sweet-cream butter, powdered milk, water, sugar, gelatine and egg;

Treating of vegetable and fruit juices to place their particles in suspension;

Producing milk or cream from plastic cream and skim milk;

Treating of fruit and vegetable extracts to make them more suitable for use in soft drinks;

Homogenizing cosmetics before they are solidified;

Homogenizing salad dressings.

Having thus described my invention, what I claim is:

1. A device adapted for emulsifying liquids under pressure, said device having inlet means for admitting the liquid to be emulsified, a compression chamber in which the liquid is emulsified, a removable plug at each end of said chamber, a plurality of small outlet passages leading from said chamber to the exterior of said device, and a plate attached to the exterior of said device in such a manner as to concentrate the flow of and prevent splashing of the emulsified liquid which is discharged from said outlet passages.

2. A device adapted for emulsifying liquids under pressure, said device having inlet means for admitting the liquid to be emulsified, a compression chamber in which the liquid is emulsified, a removable plug at each end of said chamber, a plurality of small outlet passages leading from said chamber to the exterior of said device, and a plate attached to the exterior of said device, said plate

25 having a recessed inner surface so as to form with

the exterior of said device a channel for concentrating the flow of the emulsified liquid which is discharged from said outlet passages.

3. A device adapted for emulsifying liquids under pressure, said device consisting of a single block having a single-walled compression chamber extending longitudinally through said block, an inlet passage communicating at right angles with said chamber at a point approximately midway between the ends of said chamber, a removable plug closing each end of said chamber, and a plurality of small outlet passages leading at right angles from said chamber to the exterior of said block, each of said outlet passages consisting of an inner portion of very small diameter proximate the chamber and an outer portion of larger diameter proximate the exterior of said block, said outer portion being tapered at the place where it connects with said inner portion, the sum of the diameters of said outlet passages at 20 their point of exit from said chamber being less than the diameter of said chamber, whereby the liquid is retained within said chamber until it is emulsified.
